CLAIM

The ornamental design for a housing of connector plug for optical fiber, as shown and described.

DESCRIPTION

FIG. 1 is a perspective view of the top, front and left side of a housing of connector plug for optical fiber showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a perspective view thereof with the shutter being closed.

The broken lines are for illustrative purposes only and form no part of the claimed design.
